(57) **CLAIM**

The ornamental design for storage shelf for discs and cartridges, as shown and described.

DESCRIPTION

FIG. 1 is the front perspective view of the storage shelf showing our invention, with the shelf shown broken to indicate indeterminate length, it being understood that the design continues uniformly along its length.

FIG. 2 is a reduced front perspective view of the storage shelf showing our invention, with the shelf shown with further breaks to indicate a longer indeterminate length.

FIG. 3 is an enlarged top plan view of FIG. 1.

FIG. 4 is an enlarged side view of FIG. 1.

FIG. 5 is an enlarged front view of FIG. 1.

FIG. 6 is an enlarged rear view of FIG. 1; and, FIG. 7 is an enlarged rear view of FIG. 1.
